UNITED STATES PATENT OFFICE.

ELIAS Z. BAGGETT, OF WALLACE, ALABAMA.

WAGON-SHAFT TUG.

Application filed April 16, 1923. Serial No. 632,351.

To all whom it may concern:

Be it known that I, ELIAS Z. BAGGETT, a citizen of the United States, residing at Wallace, in the county of Escambia and State of Alabama, have invented certain new and useful Improvements in Wagon-Shaft Tugs; and I do hereby declare the following to be a full, clear, and exact description of the invention, such as will enable others skilled in the art to which it appertains to make and use the same.

This invention relates to a wagon shaft tug.

It is generally aimed to provide an efficient and inexpensive means to overcome the liability of the shaft of a wagon striking the body of the draft animal upon the wheels of the wagon encountering an obstruction, and a construction which will maintain the shaft substantially straight ahead under all conditions to the end that the draft will be substantially direct and equalized with respect to the shaft.

Various additional objects and advantages, mostly servient to those stated, will appear hereinafter from a consideration of the description taken in connection with accompanying drawings.

In said drawings:—

30 Figure 1 is a fragmentary view, in perspective, illustrating the use of the improved shaft tug;

Figure 2 is a perspective view of the shaft tug alone;

35 Figure 3 is an inverted plan view of the shaft tug and

Figure 4 is a substantially central longitudinal sectional view taken in the general plane of the shaft tug.

40 Like reference characters designate like or similar parts in the different views.

In reducing the invention to practice, the device primarily consists of a rigid, preferably metallic stock or body 10. In order that its method of use will be clear, a wagon shaft has been shown at A and draft animal hames at B. This shaft and hames are to be taken as conventional and it is to be understood of course that a shaft A as usual is provided at each side of the draft animal and that my improved shaft tug is employed in pairs, one at each side of the draft animals and to coact with each shaft.

Hames B usually carry a suitable bracket

or loop as at 11 for parts of the harness and for instance the tugs. The body 10 is provided with a plurality of hooks at 12, preferably in spaced relation, adapted to detachably engage the bracket 11 as shown in Figure 1. These hooks may be of any suitable size or shape and may even be supplanted by other means to detachably connect the same to the hames.

At the end opposite to the hooks 12, body 10 is bifurcated or arched as at 13, thereby providing legs 14 and 15, the latter being longer than the former. The shaft A is adapted to be received in the arch or bifurcation 13 and the body connected to the shaft through the medium of said arch and through the medium of a strap 16. Strap 16 may be of leather or other suitable flexible material. Leg 15 is cut away or recessed as at 17 in order to provide a pin 18 to which the strap 16 is fastened as at 19, and in order to provide a lug at 20 adapted to be abutted by the strap.

Leg 14 is also recessed as at 21 so that the free end of the strap 16 may be passed therethrough and cooperate with means carried by that leg and forming a buckle. Thus a tongue 22 may be pivoted by a pin 23 to the leg 14 and at its free end be adapted to pass through selected openings 24 in the strap 16. The weight and action of shaft A on the strap 16 holds the tongue in fastening position in abutment with a flange 25 integral with leg 14.

In order to guide and more securely seat the strap 16, the legs 14 and 15 at their inner surfaces have shoulders 26 and 27, respectively, adjacent the longitudinal edges of the strap.

With the device in use as in Figure 1, having the hook 12 detachably connected to the hames or other article of harness, and the arch 13 and strap 16 buckled about the shaft A, and with both shafts of a wagon so equipped, the liability of either of the shafts, upon the wheels of the vehicle striking an obstruction, being thrust against the body of the draft animal is prevented. Thus the shafts and wheels of the wagon will be maintained substantially straight ahead under all conditions and the draft will be substantially direct and equalized.

As merely one embodiment has been illustrated and described, it is to be understood

that changes in the details may be resorted to provided they fall within the spirit and scope of the invention.

I claim as my invention:—

5. 1. In combination with a vehicle shaft and the harness of a draft animal, a substantially flat rigid body forming an attachment and interposed between them to prevent movement of the shaft into contact with the 10 body of the draft animal, means of detachable connection between said body and the harness at one end of the body, and means of separable connection disposed longitudinally of and as a continuation of the body 15 between said body and the shaft.
2. A wagon shaft tug having a substantially flat body provided with laterally extending hooks at different elevations at one end attachable to animal harness, said body 20 adjacent its other end having a buckle attachable to a vehicle shaft and disposed longitudinally thereof and as a continuation of the body.
3. A wagon shaft tug having a body 25 adapted to extend from animal harness, said

body at one end being bifurcated to engage the wagon shaft and to form legs extending longitudinally of the body and as a continuation thereof, a strap connected to one of said legs, and a tongue carried by the other leg adapted to fasten said strap about the shaft.

4. A wagon shaft tug having a body adapted to extend from animal harness, said body at one end being bifurcated to engage a wagon shaft and to form legs, said legs being of unequal length, the longer leg having a pin, a strap fastened to said pin, a lug on the longer leg adapted to be abutted by said strap, the shorter leg being recessed, a 35 tongue pivoted to the shorter leg and adapted to fasten said strap about a shaft, and both of said legs having shoulders between which the strap is guided.

In testimony whereof I affix my signature 40 in presence of two witnesses.

ELIAS Z. BAGGETT.
